UNITED STATES PATENT OFFICE

BERRY C. MOXLEY, OF HOQUILAM, WASHINGTON

AUTOMATIC OIL BURNER REGULATOR

Application filed October 3, 1928. Serial No. 309,932.

This invention relates to an automatic oil burner regulator and it consists in the novel features hereinafter described and claimed.

An object of the invention is to provide a regulating means of the character stated, which is adapted to operate automatically for producing a small or spot flame at the burner or large flame, when desired. While the device is intended to operate automatically, it may be operated manually or by hand so as to produce the character of flame desired.

A further object of the invention is to provide in combination with a burner means for producing a large or small flame, and at the same time, means for regulating the elements of the mixture of the fuel for the flame so that flames of degrees of temperature may be produced at the burner.

20 The means for controlling the mixture is operated by hand.

With these objects in view, the structure includes in combination with a burner capable of burning a mixture of oil and steam, a regulating device comprising a valve for controlling the quantity of oil supplied to the burner and a valve for controlling the quantity of steam supplied to the burner. The valves are both mounted upon a rod 30 which in turn is mounted for sliding movement and a spring is provided for urging the rod in one direction. Means are provided for limiting the movement of the rod in either of two directions. A cylinder receives 35 the end of the rod and a piston is slidably mounted in the cylinder and bears against the end of the rod. Means are provided for admitting steam pressure into the cylinder at the side of the piston so that the piston 40 may be moved in the cylinder whereby the rod is moved and the valves are correspondingly moved with relation to their seats so that the volumes of the oil and the steam are supplied to the jet to produce a spot or small 45 flame or a large flame.

In the accompanying drawings:

Figure 1 is a vertical longitudinal sectional view of the automatic oil burner regulator showing the structure and the arrangement 50 of the parts thereof.

Figure 2 is an under plan view of the regulator.

Figure 3 is a transverse section as seen on the lines 3—3 of Figure 1, looking in the direction of the arrows, and

Figure 4 is a similar view as seen on the lines 4—4 of Figure 1.

As illustrated in the drawings, the burner consists of frame sections 1 secured together by means of bolts 2. An oil chamber 3 is mounted upon one of the frame sections and a steam chamber 4 is mounted upon the next adjacent frame section. The chamber 3 is provided at its top side with a tube 5 forming an oil inlet passageway and the chamber 4 is provided at its top side with a steam inlet tube 6 forming a passageway. The tube 5 is provided at its upper portion with an interiorly located partition wall 7 having an opening 8 therein and the side wall of the tube 5 is provided with an opening 9 disposed opposite the opening 8 and spaced therefrom.

A valve 10 is adapted to close against the opening 8 and the said valve is mounted upon a stem 11 which passes through that side of the tube 5 opposite the side thereof having the opening 9. A suitable packing gland 12 is provided for preventing leakage at the point where the valve stem passes through the side of the tube. An oil supply pipe (not shown) is adapted to be connected with the upper end of the tube 5. The oil chamber 3 is provided at its forward side with a nipple 13 and a mixing jet 14 is screwed into the said nipple and is housed therein.

The tube 6 is provided at its lower portion with an interiorly located partition wall 15 having an opening 16. The side wall of the tube is provided with an opening 17 which is located opposite the opening 16. A valve 18 is adapted to close against the opening 16 and may be inserted into the tube through the opening 17 in the side walls thereof. The valve 18 is carried by a stem 19 which passes through the side wall of the tube 6 and which is connected at its end with a cross head 20. The stem 11 is also connected to said cross head. A packing gland 21 is provided at the point where the stem 19 passes through the side wall of the tube 6 to prevent leakage.

The outer ends of the stems 11 and 19 are threaded and the said threaded ends are screwed into the cross head and are secured by means of jam nuts 22 screwed upon the said stems and adapted to bear against the 5 faces of the cross head.

The tube 6 is provided with an interiorly located sleeve 23 which is located at the upper edge of the partition wall 15 and disposed diametrically across the said tube. A rod 24 10 is slidably received in the sleeve 23 and one end of the said rod passes through the cross head 20 and is adjustably secured thereto by means of clamp nuts 25 screwed upon the rod and which bear against the opposite faces 15 of the cross head. Nuts 26 and 27 are screwed upon the intermediate portion of the rod 24 and are located one at each side of the tube 6. The said nuts 26 and 27 are spaced from each other for a disposition so that 20 when one of the said nuts is in contact with the side of the tube, the other tube is spaced therefrom and vice versa. A nut 28 is screwed upon the rod 24 at a point spaced 25 from the nut 27 and a washer 29 bears against the inner face of the nut 28. A coil spring 30 is interposed between the side of the tube 6 and the washer 29 and serves to hold the washer spaced from the side of the tube.

The outer end of the rod 24 is slidably received in the inner end of a cylinder 31 and a packing gland 32 is provided at the point where the rod passes through the end of the cylinder to prevent leakage. The cylinder is carried by a frame 33 which is attached by means of bolts 34 to lateral arms formed on the chamber 4, as clearly shown in Figure 2 of the drawings. The cylinder 31 is provided at its end with a steam inlet port 35 and at its side with a steam inlet port 36. Steam pipes (not shown) may be connected 40 with the ports 35 and 36 and also with the tube 6.

A piston 37 is slidably mounted in the cylinder and bears at one end against that end of the rod 27 which passes through the end of the cylinder. The piston is located between the steam ports 35 and 36 so that when steam is admitted into the cylinder through the port 35, the piston is moved in one direction and when steam is admitted into the cylinder through the port 36, the piston is moved in the opposite direction in the cylinder.

A tubular stem 38 passes through the opposite side walls of the chamber 4 and through one of the side walls of the chamber 3. A hand wheel 39 is mounted at the outer end of the stem 38 which is closed. The stem 38 is provided at its opposite end with a head 40 adapted to move toward and away from the jet 14 and which enters the inner portion of the said jet. The intermediate portion of the stem 38 is threaded as at 41 in the chamber 4, so that when the stem is turned, 45 it also moves longitudinally across the cham-

bers. Suitable packing glands 42 are provided at the points where the stem passes through the side walls of the chambers in order to prevent leakage at said points. The stem 38 is provided at points located within 70 the chamber 4 with openings 43 which communicate with the interior of the said tubular stem and also with the interior of the chamber 4. The stem is open at that end which is adjacent the jet 14.

The automatic operation of the regulator is as follows. Assuming that the oil supply tube 5 is connected with an oil pipe and the tube 6, and the ports 35 and 36 are connected with sources of steam supply. The oil and the steam from the tubes enter the chambers 3 and 4. The steam passes through the openings 43 and through the tubular stem 38 and mixes the oil at the inner end of the jet 14. By shifting the stem with relation to the jet, the space between the head 40 and the inner end of the jet is increased or diminished whereby the proportion of the oil which is mixed with the steam is regulated. This mixture is ejected at the end of the nipple 13 where it is ignited and a flame of desired intensity of heat is produced.

The steam pressure which enters the cylinder 31 through the opening 35 moves the piston 37 in the cylinder toward the tube 6 and consequently, the spring 30 is compressed and the nut 27 is brought in contact with the side of the tube 6. The movement of the rod 24 carries the cross head 20 so that the valves 10 and 18 are moved toward the openings 8 and 16 but are spaced therefrom so that small quantities of the oil and the steam may pass through the said openings and consequently, as the pressure of the steam increases, the said valves are moved closer to the openings and as the pressure of the steam decreases, the valves move away from the openings under the tension of the spring 30 and consequently, the quantities of the oil and the steam are supplied to the jet to produce a spot or small flame or a large flame.

The tube 6 and the opening 35 may be connected with the steam source of steam supply and the steam in the said source may be generated by the flame which is produced at the jet of the burner. Thus, as the steam pressure is increased by the character of the flame, the valves of the regulator are moved to reduce the supply of oil and steam to the burner and as the pressure of the steam in the source of supply reduces the supply of the oil and the steam to the jet of the burner is increased in volume. The opening 36 may be connected with another source of steam supply and when it is desired to manually move the piston in the cylinder, the steam is permitted to enter the cylinder through the opening 36 and consequently, the valves 10 and 18 may be moved so as to permit maximum quantities of the oil and the steam to pass

through the openings 8 and 16. By adjusting the tubular stem 38 as hereinbefore described, the relative proportions of the steam and the oil constituting the mixture may be 5 regulated.

From the foregoing description of the construction of my improved apparatus, it will be seen that I have provided a simple, inexpensive and efficient means for carrying out 10 the objects of my invention and while I have particularly described the elements best adapted to perform the functions set forth, it is obvious that various changes in form, proportion and in the minor details of construction 15 may be resorted to without departing from the spirit or sacrificing any of the principles of the invention.

Having thus described the invention, what is claimed is:

20 1. A fuel regulator for oil burners comprising an oil chamber, a mixing jet leading therefrom, a steam chamber, an inlet neck extending from each chamber and having a partition therein formed with a passage, 25 valves for closing the passages in said partitions having stems projecting from the inlet necks transversely thereof and extending in opposite directions in overlapped and spaced relation to each other, a hollow stem 30 extending through said steam chamber and entering said oil chamber and terminating in an open end adapted to enter the inner end of said jet when the stem is moved towards the jet and regulate flow of oil into 35 the jet, steam inlet openings being formed in the stem within the steam chamber, and actuating means for said valves adjustably connected with the stems of the valves.

2. A fuel regulator for oil burners comprising an oil chamber, a mixing jet leading therefrom, a steam chamber, an inlet neck extending from each chamber and having a partition therein formed with a passage, 40 valves for closing the passages in said partitions having stems projecting from the inlet necks transversely thereof and extending in opposite directions in overlapped and spaced relation to each other, a hollow stem 45 extending through said steam chamber and entering said oil chamber and terminating in an open end adapted to enter the inner end of said jet when the stem is moved towards the jet and regulate flow of oil into the jet, steam inlet openings being formed in the 50 stem within the steam chamber, a cross head connecting said valve stems, a cylinder having a steam inlet at one end, a piston in said cylinder, a rod extending from said piston through the other end of the cylinder and 55 secured to said cross head, means to yieldably resist movement of the rod in a direction to 60 close the valves, and means to limit movement of the rod.

3. A fuel regulator for oil burners comprising an oil chamber, a mixing jet leading

therefrom, a steam chamber at the opposite side of said oil chamber from the mixing jet, a hollow stem extending through the steam chamber and projecting into the oil chamber towards the mixing jet, said stem delivering 70 steam from the steam chamber into the jet and being adapted to control flow of oil from the oil chamber into the mixing jet when adjusted towards and away from the jet, inlet necks leading from said chambers and provided with partitions having portions extending longitudinally of the necks and formed with openings, valves in said necks for closing the openings having stems extending transversely in the necks and projecting from facing sides of the necks, a cross head having the valve stems secured thereto, a control rod secured to said cross head, and means to shift said rod longitudinally to adjust the valves. 75

4. A fuel regulator for oil burners comprising an oil chamber, a mixing jet leading therefrom, a steam chamber at the opposite side of said oil chamber from the mixing jet, a hollow stem extending through the steam chamber and projecting into the oil chamber towards the mixing jet, said stem delivering 80 steam from the steam chamber into the jet and being adapted to control flow of oil from the oil chamber into the mixing jet when adjusted towards and away from the jet, inlet necks leading from said chambers and provided with partitions having portions extending longitudinally of the necks and formed with openings, valves in said necks for closing the openings having stems extending transversely in the necks and projecting from facing sides of the necks, a cross head having the valve stems secured thereto, a frame extending from the neck of said steam chamber, a cylinder carried by said frame and having steam inlets near its ends, a piston in said cylinder and a rod extending from said piston and secured to said cross head to adjust the valves when the piston is moved and means to yieldably resist movement of the rod in one direction. 85

In testimony whereof I affix my signature.
BERRY C. MOXLEY.
